5 Claims. (Cl. 250—27.5)

This invention relates to electron discharge devices of the kind having an external anode and a jacket on the exterior of the anode through which cooling fluid may be circulated.

5 The principal object of the invention is to provide an electron discharge device having a cooling jacket which is easily fitted in position and dismantled.

According to this invention we provide an electron discharge device having an external anode formed with external flanges, a wall encompassing the anode and having edges placed adjacent the edges of the external flanges of the anode, and a ring formed with a recess into which the adjacent edges of the anode flanges and the external wall fit and filled with packing material covering said edges, and means for pressing the ring upon said edges to form a fluid tight joint.

10 The nature of the invention will be better understood from the following description of one embodiment thereof taken in conjunction with the accompanying drawings, of which:

15 Fig. 1 is a part sectional elevation of the external anode and cooling jacket of a double ended electron discharge tube.

Fig. 2 is a half plan view partly in section on the line AB of Fig. 1, and

20 Figs. 3 and 4 are views showing constructional details.

The external cylindrical anode 1 has tapered ends 2 and 3 to which glass bulbs 4 and 5, parts only of which are shown, are fused in a well known manner. At the ends of the anode near 25 to the commencement of the tapering are fixed external rings 6 and 7 with bevelled edges 8, 9 turned outwards parallel to the anode surface. The edges 8, 9 are bevelled on the sides towards the anode. The external wall of the cooling 30 jacket is constituted by a cylinder 12 the edges 15, 16 of which are bevelled on the side away from the anode and fit closely against the edges 8, 9. Over the adjacent ends of the flanges 6, 7 and the wall 12 are placed rings 20, 21 provided with 35 recesses 22, 23 filled with plastic material 25, 26 which covers the adjacent bevelled edges 8, 15 and 9, 16 respectively. The recesses 22, 23 are formed with inturned edges 24, 24' as shown clearly in Fig. 3 to retain the plastic material 40 25, 26. Formed integrally with the cylinder 12 are ribs 13, 14 provided with holes to receive bolts 27, 28. The rings 20, 21 are provided with internally screwed recesses to receive the bolts 27, 28.

45 A plurality of bolts such as 28, 28', 28'', 28''' is provided around each of the ribs 13 and 14. The

cylinder 12 is provided with an inlet pipe 17 and outlet pipes 18, 19 for the cooling fluid.

In assembling the jacket the cylinder 12 is slipped over one of the glass bulbs 4 or 5 of the electron discharge device and placed with its edges 15, 16 against the edges 8, 9. The rings 20, 21 are then placed with the plastic material 25, 26 over the adjacent edges and the bolts 27, 28, etc., passed through the ribs 13, 14 into the recesses in the rings, and tightened until a fluid tight joint is obtained.

In order to secure more efficient cooling there may be provided inside the jacket 12, deflectors 29 and 30, each composed for example, of two half shells or several cylindrical segments maintained by two members 31 and 32, 31' and 32' of which the elevation is shown in Figure 1 and a portion of the plane view in Figure 4. These half shells may be connected by bolts such as 34, Figure 4.

The members forming the units of 29 and 30 comprise a series of bosses such as 33. These bosses leave between them a sufficient passage to give the cooling fluid a high speed over the surface of the cooling anode 1. Joints each in the form of a torus 35 and 36 of plastic material, for example, rubber, whose section in the plane of Figure 1 or 3 is in U-shape, are placed around deflectors 29 and 30 and force the fluid coming through the tube 17 to pass between the deflectors 29 and 30 and the anode 1 instead of passing between the deflectors and the jacket 12. These joints are held applied by the pressure of the cooling fluid. Openings 37 and 38 shown in Figure 3 and of which others 37', 37'' and 37''' are shown in Figure 4, may be provided in the half shells 31, 31', 32 and 32', these holes permitting the cooling fluid to exert its pressure on the joints 35 and 36.

In order to dismantle these jackets for example, for cleaning, the invention provides devices permitting the easy dismantling of the outer jacket without any other mechanical operation than the loosening of the bolts such as 27 and 28. For this dismantling it is sufficient to undo and remove the bolts such as 27 and 28 with a suitable tool, then to remove the rings 20 and 21 by pressing on the jackets 13 or 14 and taking away the ring thus removed and the outer jacket 12. Grooves 10 and 11 are provided in the outer sides 45 of the rings 6, 7 so that a suitable tool may exert pressure on the remaining ring so that it may be removed.

The deflectors and their accessory members thus become accessible which permits their easy 50

dismantling. Re-assembly is effected as previously indicated.

It will be seen that the dilation of the anode 1 forces the extremities 8 and 9 of the crowns 5 6 and 7 more into the joints of plastic material 25 or 26 which thus maintains the tightness. The jacket 12 can thus be made in a rigid manner without being provided with devices adapted to compensate the dilation of the anode.

10 It is clear that the invention is not limited to the embodiment which has just been described. It is clear, for example, that the manner in which a fluid tight joint is secured between the cylinder 12 and the anode can be applied to a single ended 15 tube, the cylinder 12 in this case being replaced by an outer wall of the jacket which is of similar shape to the anode and encompasses it at a suitable distance therefrom.

What is claimed is:

20 1. An electron discharge device having an external anode formed with an external flange, a wall encompassing said anode and having an edge placed adjacent the edge of said flange, a ring formed with a recess filled with packing 25 material and so placed that said packing material extends on both sides of and covers the edges of said flanges and said wall, means for pressing said ring upon said edges, and means for circulating cooling fluid between said wall and 30 said anode.

2. An electron discharge device having an external anode formed with an external flange, said flange being formed with an outer wedge shaped edge, a wall encompassing said anode and having 35 a wedge shaped edge placed adjacent the edge of said flange, a ring formed with a recess filled with packing material and so placed that said packing material extends on both sides of and covers the edges of said flange and said wall, means for pressing said ring upon said edges and 40 means for circulating cooling fluid between said wall and said anode.

3. An electron discharge device having an ex-

ternal anode formed with an external flange, said flange being formed with an outer wedge shaped edge, a wall encompassing said anode and having a wedge shaped edge placed adjacent the edge of said flange and having an external 5 rib adjacent said edge, a ring formed with a recess filled with packing material and so placed that said packing material extends on both sides of and covers the edges of said flange on the anode and said wall, means engaging said ring 10 and said rib on said wall to draw the two together and press said packing material against said edges, and means for circulating cooling fluid between said wall and said anode.

4. An electron discharge device having an external cylindrical anode fused to a glass bulb at each end thereof, external flanges on said anode adjacent said glass bulbs and formed with wedge shaped edges, an external cylindrical wall having wedge shaped edges placed against the edges of 20 said flanges, a pair of rings formed with recesses containing packing material and placed so that said packing material extends on both sides of and covers the said edges of said wall and said flanges, means for pressing each ring upon the 25 respective said edges and means for circulating cooling fluid between said wall and said anode.

5. An electron discharge device having an external cylindrical anode, external flanges attached to spaced points on said anode and formed 30 with wedge shaped edges extending in opposite directions, an external cylindrical wall having wedge shaped edges placed against the edges of said flanges, a pair of rings formed with recesses containing packing material and placed so that 35 said packing material covers the said edges of said wall and said flanges, means for attaching each ring to said wall so as to press against its cooperating edges, and means for circulating cooling fluid between said wall and said anode. 40
